CLAIM

I claim a new ornamental design for a shackle, as shown and described.

DESCRIPTION

FIG. 1 is a perspective view of a shackle according to my new design;

FIG. 2 is another perspective view of the shackle of FIG. 1;

FIG. 3 is a front elevational view of the shackle of FIG. 1;

FIG. 4 is a top plan view of the shackle of FIG. 1;

FIG. 5 is a left side elevational view of the shackle of FIG. 1;

FIG. 6 is a right side elevational view of the shackle of FIG. 1;

FIG. 7 is a rear elevational view of the shackle of FIG. 1; and,

FIG. 8 is bottom plan view of the shackle of FIG. 1.

The dashed lines in FIGS. 1-8 represent environment and are for illustrative purposes only and do not constitute part of the claimed design. The phantom lines in FIGS. 1-8 define the border between claimed and unclaimed matter.
